UNITED STATES PATENT OFFICE.

JOHN A. SULLIVAN, OF CLEVELAND, OHIO, ASSIGNOR OF ONE-HALF
TO I. F. HELPER, OF CLEVELAND, OHIO.

INSULATED WIRE-SUPPORT.

No. 806,937.

Specification of Letters Patent.

Patented Dec. 12, 1905.

Application filed December 15, 1904. Serial No. 238,980.

To all whom it may concern.

Be it known that I, JOHN A. SULLIVAN, a citizen of the United States, residing at Cleveland, in the county of Cuyahoga and State of Ohio, have invented new and useful Improvements in Insulated Wire-Supports, of which the following is a specification:

My invention is an improved insulated wire-support; and it consists in the construction, combination, and arrangement of devices hereinafter described and claimed.

One object of my invention is to effect improvements in the construction of the support for the insulator whereby the said support may be readily opened to enable the insulator to be readily placed therein or removed therefrom.

A further object of my invention is to effect improvements in the construction of the insulator to facilitate its attachment to the wire.

In the accompanying drawings, Figure 1 is an elevation of a wire-support embodying my improvements, and Fig. 2 is partly an end elevation of the same and partly a transverse section taken on the plane indicated by the line *aa* of Fig. 1.

The support or grip comprises a pair of semicylindrical sections A B. The former is provided on one side with a curved outwardly-extending tongue F and on the opposite side is provided with an outstanding lug G, which has a slot or notch H in its outer end, the said slot or notch being open at its outer end. The section B has on one side an outstanding lug I to bear against the lug G and which is provided with a bolt-hole K to register with the inner end of the slot or notch H. On the opposite side of the section B from the lug I is an outstanding arm or flange L, which is provided with an opening M, through which the tongue F may be passed. A bolt N is provided and the same is adapted to be placed in the opening K of the lug I and in the slot or notch H of the lug G, with its head O to bear against one of said lugs and the nut P to bear against the other lug, so that the said bolt coacts with the tongue F and the flange L to secure the two sections A B together and permit them to be readily disconnected. It

will be understood that in securing the sections A B together the curved tongue F is first inserted in the opening M, the bolt being inserted in the opening and notch of the respective lugs I G after the said sections A B have been closed together. The section B is provided in one side with an opening R for the passage of the stem of a bolt used to secure the device to a hanger and also has a socket S or recess of suitable size and shape to receive a portion of the head of said bolt.

The insulator comprises the two semicylindrical sections D E, which when placed together may be closed on a wire and are of such size and shape as to be engaged by the sections of the support or grip, the said semicylindrical sections of the insulator being provided at their ends with flanges T, which bear against the ends of the sections of the grip or support, and thereby the insulator is retained in the grip or support. In practice the insulator may be made of any suitable material, such as porcelain. The section E of the insulator is provided with a recess or socket U, which registers with the socket S of the grip or supporting section B and coacts therewith to receive the head of the hanger-bolt. It will be understood that by making the insulator of two detachable semicylindrical sections the same may be readily applied to or detached from a wire.

From the foregoing description, taken in connection with the accompanying drawings, the construction and operation of my invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

The combination of an insulated wire-support comprising a pair of semicylindrical grip-sections having means to detachably secure them together and one of said sections having a radial opening, an insulator comprising a pair of semicylindrical separable sections se-

sured together by the grip-sections, one of
said insulator-sections having a recess in one
side registering with the radial opening in
the said grip-section, and a bolt having its
head in said recess and its stem portion ex-
tending through said radial opening, substan-
tially as described.

In testimony whereof I have hereunto set my
hand in the presence of two subscribing wit-
nesses.

JOHN A. SULLIVAN.
